(57) **CLAIM**

The ornamental design for a robot arm, as shown and described.

DESCRIPTION

FIG. 1 represents a right side view of an embodiment of a robot arm showing our new design with cabling;

FIG. 2 represents a left side view thereof;

FIG. 3 represents a rear view thereof;

FIG. 4 represents a front view thereof;

FIG. 5 represents a top view thereof;

FIG. 6 represents a bottom view thereof;

FIG. 7 represents a right front perspective view thereof;

FIG. 8 represents a left rear perspective view thereof;

FIG. 9 represents a right side view of the embodiment shown in FIGS. 1-8 without cabling;

FIG. 10 represents a left side view thereof;

FIG. 11 represents a rear view thereof;

FIG. 12 represents a front view thereof;

FIG. 13 represents a top view thereof;

FIG. 14 represents a bottom view thereof;

FIG. 15 represents a right front perspective view thereof; and,

FIG. 16 represents a left rear perspective view thereof.

The broken line showing of the robot arm is included for the purpose of illustrating portions of the robot arm and forms no part of the claimed design.
